SPRING DEVICE

Herman W. Patterson, Shaker Heights, Ohio

Application June 12, 1948, Serial No. 32,575

5 Claims. (Cl. 267—1)

1

My invention pertains broadly to spring devices.

Springs of the coil and leaf type have what may be termed a positive force-to-compression ratio, that is, the more the spring is compressed, the greater the force it exerts to try to resume its original position.

An object of my invention is to provide a spring device which has a negative force-to-compression ratio which is not positive, that is, a spring device wherein the restoring force exerted is substantially constant for considerable deflection and which then becomes less and less as the spring is further compressed.

Another object of my invention is to provide a spring device which has a stabilizing effect.

A further object of my invention is to provide a spring device having a negative force-to-compression ratio and its maximum stabilizing effect at the point where it has its greatest resistance to compression.

Other objects and a fuller understanding of my invention may be had by referring to the specification and drawing.

In one of its concepts the spring device of the invention comprises a first plate and a second plate and a first and a second length spring wire. Means are provided connecting the central portion of the first length of wire to the first plate and means are provided connecting each free end of the first length of wire to the second plate. Similarly, means are provided connecting the central portion of the second of the lengths of wire to the first plate at a point spaced from the point of connection of the first length of wire. The free ends of the second length of wire are connected to the second plate together with the free ends of the first length of wire at a location intermediate the points where the central portions of the first and second wires are connected to the first plate. The lengths of the wires are such that when the wire is substantially unstressed the two plates are maintained in spaced-apart relationship.

Figure 1 is an isometric view of my spring device.

Figure 2 is a plan view of the device shown in Figure 1.

Figure 3 is an enlarged fragmental view of a portion of the spring device, and

Figure 4 is a cross-sectional view of a paper dispensing container showing the spring device in association therewith.

With reference to Figure 1, my invention comprises a flat base plate 10 having at each end

thereof a punched-out and upwardly turned tab 11 and 12. A second flat plate 13 is mounted substantially parallel to the base plate 10 by means of two lengths of spring wire 14 and 15. The plate 13 has a number of punched-out downwardly turned tabs 16 which serve to hold the ends of the wires 14 and 15. The central portion of the wire 14 fits loosely under the upwardly turned tab 11 and the ends of the wire are loosely held by the tabs 16 in the plate 13. The central portion of the wire 15 similarly is loosely held by tab 12. Each free end of each of the wire springs 14, 15 should be held by several of the tabs 16, 17 and 18 in order to maintain the alignment of the end of the wire. I have found it preferable to utilize three tabs to hold each free end of the wires, and the center tab 17 is punched out from the plate 10 with its hinge edge opposite the hinge edge of the tabs 16, 18. This positively prevents the free end of the wire from slipping out of place. The plate 13 is resiliently suspended above the plate 10 by means of the springs 14 and 15, and the springs should bow outwardly, as shown. The length of the springs 14, 15 should preferably be equal and should be such that when in their neutral position they hold the plate 13 away from the plate 10 and substantially parallel thereto. Upon compressional force being applied, tending to urge the plate 13 towards the plate 10, the springs 14 and 15 bow outwardly further than when in their neutral or unbiased position permitting the plate 13 to approach the plate 10. The location of the wires when the plates are squeezed together is shown in dotted lines in Figure 2. For a considerable deflection of the plates 13, 20 toward each other the counter-force extended by the springs 14, 15 seems to remain substantially constant, and then as the plates approach closer the counter-force decreases. This may be termed an inverse force-to-compression ratio as it is contrary to most springs which evidence a greater restoring force for greater compression distance. It is important in obtaining the maximum inverse force-to-compression ratio that the springs 14 and 15 be held loosely at 11 and 12 and is particularly important that the ends of the springs be held loosely at the plate 13. This permits the springs 14 and 15 to rotate slightly as the plate 13 is pushed toward the plate 10 thereby bowing the springs outwardly and prevents torsional forces from being built up in the springs 14 and 15. If this torsional force were permitted to be built up in the springs 14 and 15, the device would be apt to exhibit a posi-

utive force-to-compression ratio as the further together the plate were pushed the greater would be the torsional forces established. With the ends of the springs 14 and 15 held loosely by the tabs 16, it is important to provide means for preventing the ends of the springs from sliding through the tabs. This I do by providing a depression 20 in the center of the plate 13 and by causing the ends of the springs 14 and 15 to abut against the edges thereof.

In Figure 3 there is illustrated a container which is particularly useful for dispensing tissue paper or the like. A spring of the type shown in Figures 1 and 2 is particularly useful in such a container as it exerts a minimum amount of force when the container is full of paper, thereby greatly reducing the frictional forces exerted on a sheet of paper when it is withdrawn from the container. This, of course, reduces to substantially zero the sheets which are torn as they are withdrawn. The container is identified generally by the reference character 21 and comprises a bottom portion 22 and a top portion 23. These two portions are hinged together at the dispensing end 26, as is shown in detail in my pending application Serial Number 545,038, issued on February 1, 1949 as Patent No. 2,460,306, and single sheets of paper can be withdrawn from the slot 27. The catch device 24 may be used to hold the two container portions together at the end opposite the dispensing end. Reference character 25 indicates a stack of interfolded sheets of tissue which are to be dispensed one at a time from the container 21. In this container the tissue is fed from one side out through the slot 27, and, accordingly, it may be desirable, especially for some types of paper, that a spring device be positioned in the dispenser to maintain the pack of tissue toward the side from which it is dispensed.

If the spring device had a positive force-to-compression ratio, it would exert its maximum force when the pack was fully loaded and the spring compressed to its maximum extent and might thereby prevent the tissue from being easily dispensed. If the force of the spring were too great, the first few sheets of tissue dispensed might be torn in the act of withdrawing them from the container. However, with my spring device which exhibits a negative force-to-compression ratio, the spring device has its least restoring force when the dispenser is completely loaded and as the dispenser is emptied by withdrawing tissue, the spring exerts a greater and greater force to cause the remaining tissues in the container to be forced against the wall from which they are dispensed.

When used with the tissue dispensing container the spring device may be slightly modified, as is shown in Figure 4, by using one wall of the container as the base 10. In this construction there are two retainer lugs (only one of which 11 is shown) molded integral with the wall of the container and shaped to hold the center portions of the spring wires 14, 15 in a manner similar to the way in which the tabs 11 and 12 hold the wires.

A further slight modification which may be made in the device shown in Figure 4 is to utilize the wall 22 in place of the platform 13 and to anchor the free ends of the spring wires to the wall. In this modification the base 10 would be in contact with the tissue 25.

When my spring device is used with a container for dispensing tissues it is desirable that

the weight of the tissues which fill the container be sufficient to hold the springs down once they are compressed, but that the weight be insufficient in itself to compress the springs. Thus, when loading the container shown in Figure 4, the container is held in an upside-down position with the side 23 open and a new pack of paper is placed in position against the plate 13 and is pushed to compress the springs 14, 15 until the plate 13 is against the wall 22. The weight of the tissues is then sufficient to hold the plate 13 down and the case can then easily be closed.

A further important feature of my invention is that the spring device exhibits a stabilizing effect. In its extended position, as is shown in Figure 1, if a person tried to push down on one side of the plate 13, forces would be built up in the springs 14 and 15 to resist this motion and to cause the plate 13 to try to remain parallel to the plate 10. So, too, if the plate 13 were pushed sideways and slightly downward with respect to the plate 10, the springs 14 and 15 would have built up in their sides unequal restoring forces which would tend to keep the plate 13 parallel to the plate 10. This stabilizing effect is also of value in the tissue dispensing container 21 as it keeps the various sheets of tissue flat against the top wall 23 from which they are dispensed, and when the dispenser is partially empty, the tendency of the tissue to tumble about within the container is counterbalanced by a gentle pressure and stabilizing effect of the spring device.

In a typical spring device manufactured in accordance with the invention the following weight-deflection relationship has been observed, where the original or natural spacing between the plates 10 and 13 was 1 inch and the weights applied to the plate 13 tending to force it down toward the plate 10. The weights used and the deflections produced by them are given in the following table:

Spacing In Inches	Weight In Ounces
1	0
3/4	.5
5/8	1
11/16	1.0
3/4	1.4
15/16	1.0
7/8	.5

While I have described my invention with a certain degree of particularity, it is to be understood that changes may be made, such, for example, as anchoring the free ends of the spring wires 14, 15 at the plate 10 and the central portions at the plate 13, and changes may be made in the means for connecting the spring wires to the plates without departing from the spirit and scope of my invention.

I claim as my invention:

1. In a spring device, a first plate, a second plate, a first looped length of spring wire connected to said first plate and connected to said second plate, a second looped length of spring wire connected to said second plate and connected to said first plate at a point spaced from the point where the first loop of wire is connected to the first plate, the points of connection of said first and second loops of wire to said second plate lying between the points where the loops of wire are connected to the said first plate, and the size of said loops being sufficient that when the wire is substantially

unstressed the two plates are maintained in spaced-apart relationship.

2. A spring device as set forth in claim 1, further characterized by means connecting said first and second loops of spring wire to said first and second plates and permitting said first and second wires to rotate with respect to said first and second plates as said plates are moved toward each other.

3. A spring device as set forth in claim 2, further characterized by abutment means connected to said second plate against which ends of the said wires abut to prevent the wires from slipping with respect to said second plate.

4. In a spring device: a first plate; a second plate; a first looped length of spring wire; a second looped length of spring wire; means connecting said first and second loops of spring wire to said first plate and tab means integral with and displaced from the plane of the second plate connecting the first and second loops of spring wire to said second plate and permitting said first and second wires to rotate with respect to said first and second plates as said plates are moved toward each other; said second looped length of spring wire being connected to said first plate at a point spaced from the point where the first loop

of wire is connected to the first plate, and the size of said loops being sufficient that when the wire is substantially unstressed the two plates are maintained in spaced-apart relationship.

5. A spring device as set forth in claim 4, further characterized in that said first and second loops of wire have free terminal ends which terminate at said second plate, and said means for connecting said first and second loops of wire to said second plate comprise a plurality of tabs for connecting each free end to said second plate.
